UNITED STATES PATENT OFFICE

SYDNEY JAMES BRITIFFE TULLY AND OLIVER EVAN YEO, OF NEWARK-ON-THE-TRENT, ENGLAND

APPARATUS FOR MAKING MIXED WATER GAS AND COAL GAS

Application filed November 11, 1927, Serial No. 232,602, and in Great Britain December 31, 1926.

Carburetted water gas suitable for heating and lighting purposes has heretofore been produced in plant comprising a gas producer designed to contain coke and provided at the bottom with inlets for air and steam, a retort arranged above and in direct communication with the top of the gas producer and designed to contain coal or other carbonaceous fuel (hereinafter referred to as coal), a heating jacket charged with chequerwork surrounding the retort and in communication with the top of the gas producer through a series of openings, usually called nostrils, a gas carburetting chamber and two valve controlled conduits (hereinafter called for distinction A and B) whereby the upper ends of the heating jacket and retort can be connected alternately to the carburetting chamber. In the working of such plant, for the production of carburetted water gas, fuel in the gas producer is raised to a state of incandescence by blowing air therethrough and the resulting blow gases have been caused to flow through the nostrils into the heating jacket and thence through the associate valve controlled conduit A into and through the carburetting chamber the hot gases finally escaping through a snift valve into the external atmosphere or elsewhere, as may be desired, either direct or through a gas fixing chamber, secondary air being admitted to the heating jacket and carburetting chamber, if desired, to effect more or less complete combustion of the blow gases passing therethrough and the production of a high temperature therein. During this blowing stage the valve controlled conduit B is closed so that volatile products distilled from the coal in the heated retort will descend through the retort and flow into the heating chamber with the blow gas and be carried forward therewith. After the heating chamber and the carburetting chamber have in this way been raised to a sufficiently high temperature,—the air inlet valve and snift valve are closed and steam is admitted to the lower end of the gas producer and thence passed through the incandescent fuel in the gas producer to produce water gas.

According to one method of working, the

resulting water gas is passed through the nostrils into the heating chamber and thence through the valve controlled conduit A into the heated carburetting chamber and there in carburetted by volatile hydrocarbons produced by the cracking, due to the heat of the chamber, of liquid hydrocarbons or oil fed into such chamber the valve controlled conduit B being closed so that volatile hydrocarbons evolved from the coal in the retort will pass downward therethrough and flow into the heating chamber with the water gas and thence pass in admixture therewith into the carburetting chamber, the carburetted water gas thus produced passing from the chamber, it may be through a gas fixing chamber in series therewith and previously heated by the blow gases, into a gas main for subsequent purification. Or according to another method, the valve controlled conduit A is closed and the valve controlled conduit B opened, so that the heated water gas produced in the gas producer is caused to flow upward through the coal in the retort and become mixed with volatile hydrocarbons evolved from the coal by the heat of the jacket and water gas and the mixture of water gas and volatile hydrocarbons caused to pass through the valve controlled conduit B into the carburetting chamber and be therein carburetted like the mixed water gas and volatile hydrocarbons passed through the heating jacket into the carburetting chamber according to the first method.

It has been found in practice that when working according to the first mentioned method of producing carburetted water gas the volatile hydrocarbons evolved from the coal in the retort, are overcracked in passing through the surrounding heating chamber and that the retort cannot be kept sufficiently hot to carbonize effectively the coal descending therein, and that the secondly mentioned method of producing carburetted water gas, the water gas having given up a large portion of its sensible heat to the coal within the retort, reaches the oil carburetting chamber in a cooled condition. Also, the valuable low temperature tar vapours given off by the

coal in the retort are subjected to cracking in the oil carburetting chamber.

Now the present invention has for its object to overcome the above mentioned disadvantages and enable gas of different thermal values to be simultaneously produced in an advantageous manner. It also has for its object to avoid the use of gas valves between the heating jacket and retort and the carburetting chamber, such valves being a source of much trouble and expense.

To this end, in gas making plant of the type referred to the upper end of the retort is provided with a valve controlled gas outlet pipe 15 unconnected with the carburetting chamber but connected to a suitable seal pot or other receptacle, and the upper end of the heating chamber surrounding the retort is directly connected to the oil carburetting chamber 20 by a valveless conduit that is always open for the free passage of gas therethrough. The outlet of the oil carburetting chamber is connected as heretofore, to a water seal box, either direct, or through a gas fixing chamber, and is provided with a snift valve.

In the accompanying drawing, Figs. 1, 2 and 3 are vertical sections showing three different constructions of gas producing plant of the kind referred to embodying the present invention.

Fig. 2a is a horizontal section of the retort and its jacket taken on the line A—B of Fig. 2.

In Fig. 1, 1 is the water gas generator adapted to contain coke, 2 is the superposed retort to be charged with coal introduced through the valve controlled fuel inlet 3, 4 is the heating chamber which is provided with refractory bricks 5 arranged in staggered relation and connected to the upper part of the gas generator through the nostrils 6, while 7 and 8 are inlets for air and steam respectively to the ash pit below the grate 9 of the gas generator, 10 a valve controlled pipe connected to an annular chamber 11 for admitting secondary air to the heating chamber 4, 12 a carburetting chamber provided at the top with an inlet pipe 13 for the liquid hydro-carbon or oil to be cracked 50 for carburetting water gas flowing through the chamber, and with a valve controlled secondary air inlet pipe 14 and at the bottom with an outlet 15 connected to the lower end of a gas fixing chamber 16, the latter chamber 55 containing chequerwork 17 and provided at the top with a snift valve 18 and a gas outlet pipe 19 for connection to gas purifying or other apparatus, not shown, as heretofore usual. The carburetting chamber 12 may, 60 although not so shown, be provided with refractory chequerwork, as heretofore, and be provided at the bottom with a supplementary air inlet, as indicated at 14a. The heating chamber 4 in this example surrounds 65 the retort 2 and is formed between the latter

and an annular wall or jacket 4a. In such plant according to the present invention, the retort 2 is not adapted to be connected to the carburetting chamber 12 but is provided with a gas outlet pipe 20 that is unconnected with the carburetting chamber and by which gas can be led from its upper end to a water seal pot and thence passed to any desired gas treatment plant, not shown. The pipe 20 may be provided with a supplementary pipe 20a connected to the foul gas main, not shown. Also, according to the present invention, the upper end of the heating chamber 4 is in direct free and open communication with the upper end of the carburetting chamber 12 75 through a valveless conduit 21.

In the modified construction shown in Figs. 2 and 2a, the carburetting chamber 12 is formed in a portion of the space between the retort 2 and jacket 4a that is separated by vertical walls 4b from the portion thereof containing the refractory chequerwork 5 and constituting the heating chamber 4, the upper end of the said carburetting chamber 12 being in free and open communication at the top through the chamber 21a with the top of the said heating chamber 4, the construction in other respects being similar to that shown in Fig. 1.

In the further modified construction shown in Fig. 3, the carburetting chamber 12 is shown as of relatively larger size than in the other figures and provided at the bottom with a secondary air inlet 22 and with an outlet 15 that may be connected to a gas fixing chamber, as in the other figures, or to the lower end of a waste heat tubular steam generator, not shown, each provided with a snift valve and a gas outlet pipe as in Figs. 1 and 2.

With plant constructed as described, gas of different thermal values can be produced simultaneously in an advantageous manner.

Thus two qualities of carburetted water gas can be produced as follows:—

The coke in the gas producer is first blown to incandescence by admission of air through the inlet 7, the blow gases thus produced being caused to travel up through the heating chamber 4 and by way of the valveless conduit 21 through the carburetting chamber 12 and thence through the gas fixing chamber 16, if used, to the atmosphere through the snift valve 18. Secondary air may be admitted through the valve controlled inlet pipes 10 and 14 to cause combustion of the blow gases during their passage through the heating and carburetting chambers 4 and 12. During this air blowing stage, the gas outlet pipe 20 from the top of the retort is opened only sufficiently to allow of the volatile products including same hydrocarbon evolved by distillation of the coal in the retort 2 escaping, or alternatively, the said pipe may be closed and the said volatile

products including some hydrocarbon be drawn off through the off-take pipe 20^a, so that in either case they are conserved and not caused to pass downward through the retort and into the heating chamber 4 and be cracked therein.

When the heating chamber 4 and carburetting chamber 12 have been raised to the necessary temperature, the air supply pipes 7, 10 and 14 and snift valve 18 are closed. Steam is then admitted through the inlet 8 to the gas generator 1 to form water gas and the valve in the gas outlet pipe 20 from the top of the retort 2 is opened and oil is admitted through the oil inlet pipe 13 to the carburetting chamber 12. A portion of the water gas from the generator is caused to pass up through the coal being carbonized in the retort 1 and become mixed with the rich coal gas evolved from the coal, the enriched water gas of high thermal value being led away by the outlet pipe 20. The remainder of the water gas being generated in the gas producer is caused to pass through the nostrils 6 and heating chamber 4 and thence direct into the heated carburetting chamber 12 where it is enriched by the oil gas produced by decomposition of the oil admitted thereto and cracked therein. The two separate streams of carburetted water gas of different thermal values thus produced, are led away for separate treatment and storage. The proportion of water gas passing through the carburetting chamber 12 can be controlled by regulating the back pressure on the gas outlet 15 therefrom, or by other suitable known means.

At the end of the water gas making period, the valve in the gas outlet pipe 20 is closed, or partially closed, and the oil inlet pipe 13 is closed. The enriched gas remaining in the carburetting chamber 12 can be removed by any of the known methods, such as by scavenging with water gas, air blow gas or reverse steaming. The foregoing air blowing and water gas making operations are then repeated.

What we claim is:—

1. In a mixed water gas and coal gas making plant, a water gas generator, a coal carbonizing retort arranged above and in free and direct communication at its lower end with the upper end of said generator, a vertical heating chamber and a vertical carburetting chamber each formed in one structure with said retort and having their inner walls formed by said retort, and a gas outlet pipe extending from the top of said retort and unconnected with said carburetting chamber, the lower end of the heating chamber being in communication through ducts with the upper end of said gas generator and the lower end of said retort, and the lower end of said carburetting chamber having a gas outlet, and the upper ends of said

heating chamber and carburetting chamber being in free, direct and constant communication with each other through a valveless passage within the structure.

2. In a mixed water gas and coal gas making plant, a water gas generator, a coal carbonizing retort arranged above and in free and direct communication at its lower end with said gas generator, a jacket spaced from and surrounding said retort, a heating chamber formed by and between said retort and a portion of said jacket, and a carburetting chamber formed by and between said retort and another portion of said jacket, the lower end of said heating chamber being in communication at its lower end through ducts with the upper end of said water gas generator and the lower end of said retort and at its upper end in free, direct and constant communication with the upper end of said carburetting chamber through a valveless passage, and said carburetting chamber having a gas outlet at its lower end.

3. In a mixed water gas and coal gas making plant, a water gas generator, a coal carbonizing retort arranged above and in free and direct communication at its lower end with said gas generator, a jacket spaced from and surrounding said retort, vertical walls connecting said retort to said jacket and arranged to divide the space between said retort and jacket into two vertical chambers, one of which, constituting a heating chamber, is in direct communication at its lower end with the upper end of said gas generator and the lower end of said retort, and the other chamber, constituting a carburetting chamber is in free, direct and constant communication at its upper end with the upper end of the heating chamber and has a gas outlet at its lower end, and a gas outlet pipe at the upper end of said retort and unconnected with said carburetting chamber.

Signed at Newark, England this twenty seventh day of October, 1927.
